JEWELRY

Murray Slater, Brooklyn, N. Y.

Application August 1, 1942, Serial No. 453,197

5 Claims. (Cl. 63—15)

This invention relates to jewelry in general, and particularly to such articles of jewelry which are adapted to contain pictures, mirrors, or other devices, which may be inserted into or removed from such jewelry articles, and which may be covered while the jewelry is being worn.

One of the objects of the present invention is to provide an article of jewelry, such as a finger ring, wherein a portion thereof is sufficiently enlarged and recessed for the reception of pictures or the like, and wherein means are provided for fully covering the recess and the picture therein, and for securely locking the cover in its recess-closing position.

Another object of this invention is to provide novel locking means for the cover of the device, which not only assure the closing of the cover over the recess, but which also prevent an inadvertent opening movement of the cover while in its closing position.

The foregoing and further objects of the present invention will become more fully apparent from the ensuing description, reference being had to the accompanying drawing, wherein:

Fig. 1 is a perspective view of my device in its presently preferred form;

Fig. 2 illustrates a top view of the device, with a portion thereof removed;

Fig. 3 is an enlarged, detail view of the locking arrangement of my device;

Fig. 4 is a partial cross sectional view taken on line 4—4 of Fig. 2; and

Fig. 5 is a similar cross sectional view through a modified form of my device.

Referring now specifically to the drawing, numeral 10 denotes a finger ring having an enlarged body portion 11, wherein is provided a recess 12, adapted for the reception of a picture, mirror, or other like articles intended to be carried with the ring. Extending from enlarged body portion 11 are projections or pins 13 and 14, disposed opposite to one another and externally to the periphery of the recess. These projections are provided with heads 15 and 16, respectively.

Projection 14 serves as a pivot or hinge for cover plate 17, which latter is adapted to slide over the top edge of recess 12. Opposite its hinge connection in engagement with projection 14 cover plate 17 is provided with a locking dog 18 and a stop handle 19. Projection 13 is preferably in the form of a pin 20, around which is formed an annular locking instrumentality having a small, peripheral recess or depression. In Figs. 2, 3 and 4 such locking instrumentality is shown

5 at 21 and comprises a split spring ring the ends of which do not meet, but form a recess between them. One end of the ring comprises a lip which lies in the path of the movement of locking dog 18. This lip is adapted to somewhat yield to the pressure exerted by the dog. The moment the latter has passed lip 22, it is locked in the recess between the two ends of the ring. At this interlocking position between the dog and the 10 ring ends stop handle 19 abuts with the periphery of the ring body, as clearly illustrated in Fig. 3. Ring 21 is preferably soldered or welded in its correct position, preferably so that lip 22 remains free while the other end of the ring is fixed, and the recess formed between its ends faces pivot 14 of closure 17.

15 It will be observed from Fig. 4 that head 15 of pin 20 is of a sufficiently large diameter so that it extends over locking ring 21. The head also 20 partially covers locking dog 18 and stop handle 19 when cover 17 is in its recess-closing position.

25 In the modified form shown in Fig. 5, projection 13' constitutes an extension of body 11, which extension projects above the upper edge 25 of the recess, and through which extension passes a headed pin 23. The head 15' of this pin also extends beyond the contour of extension 13', and is intended to partially overlie dog 18 and handle 19 of the cover.

30 Projection 14, serving as hinge for the cover plate, is shown in all figures to include pins 24. Similarly projections 13 and 13' preferably are made by the use of headed pins. (20, 23.) The ends of the pins of both projections terminate 35 within ring body 11 and are preferably soldered in place, as clearly indicated at 25 in Figs. 4 and 5. The locking means of projections 13 and 13' constitute, in both modified forms, annuli surrounding the respective pins, and which annuli 40 are provided with snap recesses adapted for the reception of locking dogs 18.

Operation

45 When cover 17 is to be brought into its recess-closing position, it is operated by means of handle 19 until dog 18 engages the snap recess of the locking instrumentality in either of the two modified forms illustrated. When dog 18 passes the projection of the locking instrumentality, such as lip 22 of ring 20 shown in Fig. 4, the cover snaps into its locking position. At the same time handle 19 is brought into abutment with the rounded portion of the locking projection, such as ring 21. Since heads 15 or 15' partially overlie both dog 18 and handle 19, the 55

movement of the locked cover away from the recess in upward direction is effectively prevented. The head of the pin also sufficiently covers handle 19 so that the latter will not be readily subject to an inadvertent dislocation, thereby preventing the cover from sliding open. In order to move the cover to its opening position, the end of a finger-nail or a simple tool must be inserted between heads 15 or 15' and the end of handle 19.

While the accompanying drawing illustrates a ring only, it is quite obvious that the recess and cover construction, together with the locking instrumentalities employed, may be applied to any other article of jewelry, and I wish it to be understood that I shall have the right to apply the construction described to any such jewelry article; and I further wish it to be understood that changes and improvements which may become necessary in the course of the manufacture of the device may be incorporated without departing from the broad sense of this invention, as defined in the annexed claims.

I claim:

1. In a finger ring including an enlarged, recessed body portion and a cover plate for covering the recessed part thereof, two oppositely placed, headed pins extending from the body and disposed exteriorly to the recessed body portion and projecting above the latter, one of the pins serving as pivot for the cover plate, a locking ring associated with the other pin beneath the head thereof, the cover plate having a locking dog, adapted to engage said locking ring, and a stop handle, said locking ring of the other pin comprising an annular formation having a recess, the latter serving for accommodating and interlocking with said locking dog when the cover plate covers the recessed body portion, the stop handle of the cover plate being adapted to abut with the annular formation of the locking ring, and the head of the said other pin being adapted to extend over said locking dog and said stop handle.

2. In a finger ring including an enlarged recessed body portion having a cover plate, locking means for the plate when the latter is in a covering position, said locking means comprising a projection extending from and above the enlarged recessed body portion and exteriorly to the latter's periphery, a locking ring provided with said projection and having a recess at its

periphery, said cover plate having a locking dog for engagement with the peripheral recess of said locking ring, and an enlargement provided with the projection above said locking ring and being adapted to cover said dog while in engagement with said recess.

3. In a finger ring including an enlarged, recessed body portion having a hinged and sliding cover plate, adapted to slide over said recessed body portion, locking means for said cover plate comprising a locking dog and a stop handle, provided with the cover plate, and a fixed locking instrumentality extending from the ring body and above and exteriorly to its recessed portion, and including a peripherally recessed locking ring, the latter being adapted to cooperate and interlock with said locking dog and the stop handle of the cover plate when the latter is in a recess-covering position.

4. In a locking device for a locket ring having a recessed body portion and a hinged cover plate for the recess, a headed projection disposed substantially opposite the pivot of the cover plate and extending from the ring body and above and exteriorly to its recessed portion, a locking ring forming a part of the projection beneath its head and having a peripheral recess substantially facing the pivot of the cover plate, the latter having a locking dog and a stop handle, the former being adapted to engage and interlock with the recesses in the locking ring, and said stop handle being adapted to abut with the body of the locking ring when the cover plate covers the recessed body portion of the ring.

5. In an article of jewelry including a recessed body portion and a pivoted cover plate therefor, a locking instrumentality for the cover plate comprising a projection arranged opposite the pivotal point of the cover plate and disposed exteriorly to and extending above the edge of the recessed body portion, said cover plate having a locking dog and a stop handle, both forming parts of the cover plate and being adapted to cooperate with said locking instrumentality, the latter consisting of a ring formation having a peripheral recess disposed opposite the pivot of the cover plate, said peripheral recess being adapted to accommodate the locking dog, and the body of the ring formation serving as abutment for the stop handle.

MURRAY SLATER.
